UNITED STATES PATENT OFFICE.

HENRY BERNSTEIN, OF PHILADELPHIA, PENNSYLVANIA.

DESIGN FOR A NECKWEAR FABRIC.

No. 38,932.

Specification for Design.

Patented Dec. 3, 1907.

Application filed September 14, 1907. Serial No. 392,933. Term of patent 3½ years.

To all whom it may concern:

Be it known that I, HENRY BERNSTEIN, a citizen of the United States, residing in the city and county of Philadelphia, State of Pennsylvania, have invented a new, original, and ornamental Design for a Neckwear Fabric, of which the following is a specification, reference being had to the accompanying drawing, forming part thereof.

The figure is a plan view of a piece of neckwear fabric, showing my new design.

I claim:

The ornamental design for a neck-wear fabric, as shown.

HENRY BERNSTEIN.
